INSECTICIDE VAPORIZER

Jules Laibow, Merchantville, N. J., assignor to
Cardinal Chemical Corporation, Philadelphia,
Pa., a corporation of Pennsylvania

Application June 20, 1951, Serial No. 15,613

Term of patent 14 years

(Cl. D31—3)

To all whom it may concern:

Be it known that I, Jules Laibow, a citizen of the United States, residing at Merchantville, Camden County, New Jersey, have invented a new, original, and ornamental Design for Insecticide Vaporizer, of which the following is a specification, reference being had to the accompanying drawing, forming a part hereof.

Figure 1 is a perspective view of an insecticide vaporizer showing my new design.

Figure 2 is a top plan view of the insecticide vaporizer of Fig. 1.

Figure 3 is a side elevational view of the insecticide vaporizer shown in Figs. 1 and 2.

The other side of the insecticide vaporizer is like the side shown in Fig. 3.

I claim:

The ornamental design for an insecticide vaporizer, as shown and described.

JULES LAIBOW.
